UNITED STATES PATENT OFFICE

HENRY E. KONDOFF, OF NEW YORK, N. Y., ASSIGNOR TO THE LOX SEAL CORPORATION, OF BROOKLYN, NEW YORK, A CORPORATION OF NEW YORK

FASTENING MEANS

Application filed April 20, 1926. Serial No. 103,210.

My present invention relates generally to packaging, and has particular reference to a fastening device to be employed in connection with boxes, cartons, bales and similar 5 packages.

It is among the more important objects of my invention to provide a fastening device for securing portions of a package or container against separation in such a manner 10 that removal of the fastening device and consequent opening of the package, cannot be accomplished without detection.

It is another object of the invention to provide a fastening device which comprises relatively simple constituent parts of a character which are inexpensive from a manufacturing standpoint, the device being easy to utilize without any need for skill, and competent and efficient in fulfilling its function.

According to one feature of my invention I contemplate associating with a binding member having a free operative end, an independently applicable complimentary locking member which is provided with means for cooperating with the binding member to permit automatically irremovable engagement thereof with said free end.

The type of binding member which is used will depend upon requirements and circumstances, and it will be understood that my invention will have a wide range of applicability inasmuch as the binding member may comprise any of numerous shapes, forms and constructions. In a preferred embodiment, I 35 contemplate utilizing binding members in the form of studs or tie elements. In either event, the stud or tie element is provided with a free operative end of a character to permit engagement therewith of a locking member 40 of the character hereinbefore referred to.

Another feature of my invention lies in providing a locking member which may be used interchangeably with any type of binding member; and more particularly, in cases 45 where the binding members comprise studs or elongated tying elements, the locking member is of such a nature and construction that it is applicable with equal facility to either the stud or the tie member.

It is another object of my invention to pro-

vide a binding member in the nature of a stud which may be used simultaneously for the additional purpose of retaining overlying portions of the box or container in position. With this object in view, a feature of 55 my invention lies in providing a binding member of this character with means for temporarily retaining overlying layers of material together before the locking member hereinbefore referred to is applied.

In a preferred embodiment, the means which I associate with the locking member is of a character which will permit movement of the locking member with respect to the free operative end in only one direction, 60 namely into engagement therewith, and although such cooperation may be accomplished in a number of ways, I prefer to provide the locking member with a temporarily 65 expandible element adapted to engage with the free operative end in a manner which permits movement of the latter with respect to the expandible member in only one direction.

It is another feature of my invention to provide a locking member which may be utilized in conjunction with an elongated binding or tie member which provides a plurality of free operative ends. Thus, in a case where the binding member comprises an elongated strap or similar device which is 70 adapted to encircle the box or container, the locking member is of a character to engage with the free ends of the binding member in a manner which automatically locks it in 75 inseparable association with each end, and 80 hence retains the ends themselves in inseparable association with each other.

A preferred construction of the locking member provides the latter in the form of a button-like casing within which the expandible element is disposed in an inaccessible 85 manner. The casing is provided with registering openings in its opposite sides, the 90 openings being of an area substantially equal to the area of the free operative ends of the binding members, whereby each free operative end may be threaded through the casing in either direction. Thus, in a case where 95 two free operative ends are brought together, as where a tie member encircles a box, the 100

ends may be threaded through the casing in opposite overlapping directions; and inasmuch as the locking member is constructed to permit movement of each end through the casing in only its entering direction, the ends 5 may be adjusted to increase the over-lapping and thereby tighten the binding member, but retroactive movement of each end is prevented.

10 For cooperation with a locking member of preferred construction, I prefer to provide the free operative end of the binding member with one-way teeth adapted to engage with the expansible element within the locking member.

15 In a contemplated utilization, wherein two oppositely disposed overlapping ends are threaded through the locking member, it is a further feature of the invention to provide these ends with means for preventing movement of one from permanently expanding the expansible element so that it would be possible to withdraw the other free end.

20 For the attainment of the foregoing objects and such other objects as may herein-after appear or be pointed out, I have illustrated several embodiments of my invention in the accompanying drawings in which:

25 Fig. 1 is an exploded view of a box or carton having a body portion and a cover portion, and having one embodiment of the invention associated therewith;

30 Fig. 2 is a similar view, showing the cover portion in position, and a locking member applied to one of the binding members;

35 Fig. 3 is a fragmental cross-sectional view taken along the line 3—3 of Fig. 2;

40 Fig. 4 is a cross-sectional view taken along the line 4—4 of Fig. 3;

45 Fig. 5 is an enlarged exploded view of a locking member and a binding member of the character illustrated in Figs. 1, 2 and 3, a portion of the locking member being broken away to reveal the interior thereof;

50 Fig. 6 is a view similar to Fig. 2 showing a different type of binding member associated therewith;

55 Fig. 7 is an enlarged view, partly in section, of the free terminal ends of the binding member shown in Fig. 6; a locking member being illustrated in association therewith;

60 Fig. 8 is a cross-sectional view taken along the line 8—8 of Fig. 7;

65 Fig. 9 is an exploded view, on an enlarged scale, of a locking member unassociated with any binding member.

Referring to the drawings, and particularly to Figs. 1, 2 and 3, I have illustratively shown a box which comprises a bottom or body portion 10 and a complementary top or cover portion 11, each thereof being of knock-down construction so that portions thereof comprise superimposed layers of material. It will be observed that I have shown 70 a construction wherein the four corners of

each of the body and cover portions are constituted of three overlying layers. In accordance with my invention, I provide a fastening device which will not only serve to hold the cover portion in inseparable association with the bottom portion, but which will simultaneously serve to hold the overlying layers of material together, and thereby retain each box portion in set-up condition, prior to the complementary association of the 75 portions 10 and 11 with each other. For a purpose of this character, I provide a binding member in the form of a stud illustrated more clearly in Figs. 3 and 5.

80 Referring now to the latter figures, it will be observed that I have constructed a stud having a base 12, a shank 13, a mid-portion 14 and an end portion 15. The shank 13 may be substantially circular, or at least somewhat rounded, in cross-section, whereas the 85 portions 14 and 15 are preferably substantially flat. It will be observed upon viewing Fig. 5 that the stud is preferably constructed from a single blank of material suitably stamped and doubled on itself along a line which will 90 then constitute the foremost edge of the end portion 15. The side edges 16 of the end portion 15 are preferably made to converge toward the outer end of the stud; the mid-portion 14 is of reduced width with respect 95 to the end portion 15, so that a shoulder 17 is provided therebetween. Similarly the shank 13 has a smaller diameter of width than that of the mid-portion 14, and thereby a shoulder 18 is provided whose function will 100 be presently described.

105 The stud is initially associated with the box or container by passing it through the overlying portions thereof in a manner which will project the free end 15 outwardly of the box portion. For this purpose, I prefer to provide suitably positioned slots within the walls of the box portion so that the passage therethrough of the end portion 15 of the stud may be facilitated. By then turning the stud through approximately 90 degrees, so that the end portion 15 and the mid-portion 14 will lie at substantially right angles to the slot, the superposed layers of material will be firmly held and retained between the base 12 and the shoulder 18. I 115 have indicated one set of such superposed layers in Fig. 1 by the reference numeral 19. It will thus be seen that the shoulder 18 provides means for retaining the box portion in 120 set-up condition.

125 In Fig. 1 I have illustratively shown a stud 20 in a position projecting through the wall of the portion 10 before having turned through 90 degrees; and I have shown a stud 21 projecting through the superposed layers 19, and turned through 90 degrees to hold these layers together. The cover portion, which may be of similar construction, is also provided with slots 22 suitably posi- 130

tioned to register with the projecting ends of the studs which have been passed through the walls of the portion 10. It will be understood that the slots 22 are disposed at right angles relatively to the slots in the portion 10, so that the cover 11 may be associated with the body portion 10 after the studs have been turned in the manner illustratively shown by the stud 21. After the cover portion 11 has been applied, the studs are preferably again turned through approximately 90 degrees, thereby bringing them into the positions assumed by them when they were initially passed through the portion 10. This second turning of the studs temporarily retains the cover portion in close association with the body portion 10.

The independently applicable locking member is then ready to be applied. Referring to Figs. 5 and 9, it will be observed that the locking member comprises preferably a button-like case 23 which may be constructed of two parts, a base 24 and a cover 25, each thereof having an upturned peripheral flange. The outside diameter of the flange on the portion 24 is approximately the same as the inside diameter of the flange on the portion 25. This permits the portions 24 and 25 to be assembled by frictional engagement of the respective flanges. If desired, the outside flange, that is the one carried by the portion 25, may be clenched after the portions 24 and 25 have been assembled so as to hold them together. Within the casing thus constituted, there is disposed an expansible and resilient member which I prefer to provide in the form of a ring or loop 26 of wire or the like. In the opposite walls of the casing I provide registering openings or slots 27, which are of a length slightly greater than the unexpanded diameter of the ring 26. The ring 26 is loosely disposed or carried within the casing, and it will be evident that it is totally inaccessible for any purposes other than those for which engagement therewith was contemplated.

The slots 27 are of a size to permit passage therethrough of the terminal end or ends of a binding member. Accordingly, the locking member may now be applied over the end of the stud 21, and the engagement of the edges 16 with the ring 26 will cause the latter to expand and permit the passage through the locking member of the end portion 15. By forcing the locking member onto the stud, the ring 26 may be made to pass the edges 16, and it will suddenly collapse about the mid-portion 14. In this position, the shoulders 17 will prevent removal of the locking member. I prefer to make the mid-portion 14 of a length substantially equal to the total thickness of the locking member (see Fig. 3), and it will now be understood that the application of the locking member will force the superposed layers of the cover portion 11

onto the shank 13 along with the layers 19 of the body portion 10.

Reference to Fig. 3 will illustrate clearly how the locking member has been associated in inseparable engagement with the stud, and how the removal of the cover 11 from the body portion 10 has been rendered impossible without detection.

This irremovable engagement of the locking member with the free terminal end of a binding member, such as the stud hereinbefore described, is illustrative of the engagement between the locking member and the free terminal ends of binding members of slightly different character. In Fig. 6 I have shown a binding member in the form of a metal strap 28, the strap being of indeterminate length and having free terminal ends which may be brought together into preferably overlapping association with each other, so that the strap will encircle the container. My invention contemplates association with these free terminal ends of the locking member hereinbefore described so as to retain them in inseparable association with each other and still permit relative movement of the ends whereby the tension of the strap 28 may be increased.

In Fig. 7 I have illustrated the overlapping ends of the strap 28 on an enlarged scale. For the purpose of permitting engagement of the character contemplated between the free terminal ends and the locking member, I provide each terminal end with a series of one-way teeth, the oblique edges of the teeth being arranged to converge toward the end. Referring more particularly to the free terminal end 29 (each of the ends being similarly constructed) it will be seen that I have provided a series of teeth 30 each of which comprises a converging edge 31 and a rear transverse locking edge 32. The edges 31 of the foremost teeth are continued forwardly and unite at the foremost end along a rounded edge 33 which facilitates the insertion of the end through the locking member.

The edges 31 fulfill the same function as the edges 16 of the stud hereinbefore described; and the locking edges 32 constitute shoulders which correspond to and function substantially like the shoulders 17 of the stud. It will be understood that the end of the strap is threaded through the locking member in much the same way that the end 15 of the stud was threaded therethrough, and it will be evident that the engagement between the teeth 30 and the expansible element 26 will permit movement of the end relatively to the locking member in only one direction, namely the entering direction. It will be also evident that retroactive movement of the end with respect to the locking member is efficiently prevented by the engagement of the locking edges 32 with the expanded element 26.

The width of the slots 27 is of sufficient

magnitude to permit both of the free terminal ends of the strap 28 to be threaded through the locking member, and preferably in overlapping positions and in opposite directions. In this manner, the extent of the overlap may be increased to tighten the strap about the container, but it will be evident that loosening of the strap is totally prevented. As an added precaution, and as a feature of my invention, I provide means for preventing prolonged expansion of the element 26 (by insertion of one of the ends) whereby withdrawal of the other end might be effected. For this purpose, I provide the teeth along an end portion which is of slightly reduced width with respect to the width of the main portion of the strap 28. This reduction in width manifests itself by the shoulder 34 which is provided between the body portion of the strap and the rearmost tooth. For the purpose of increasing the effectiveness of this shoulder 34, I provide a straight, non-converging portion 35 between the rearmost tooth and the body portion of the strap. The provision of the shoulder 34 prevents the insertion of one end to such an extent that the expandable element 26 might be permanently expanded by engagement over the body portion of the strap; because although tightening of the strap is possible, nevertheless the extent of this tightening is limited, and, after either end has been passed through the locking member to a certain extent, the expandable element 26 will engage with the shoulder 34 and prevent further threading of the end.

It will thus be seen that I have provided means for inseparably associating each terminal free end of the strap 28 with the locking member, and hence associating the free terminal ends irremovably with respect to each other.

I prefer to provide the ends of the strap with a series of holes 36 which facilitates tightening of the strap by providing engageable portions. That is, a suitable tool may be inserted into any of the holes 36 so as to secure a firm grip thereon.

I also prefer to provide the free terminal end 15 of the stud with an opening 37. This opening is provided for the purpose of permitting the passage through each stud of a continuous binding rod or element which may be made to pass about the container substantially at right angles to the passage of the strap 28, but it will be understood that the provision of the opening 37, or of the holes 36 is entirely optional and does not materially affect the nature of my invention.

It will be obvious that various changes in the details herein described and illustrated for the purpose of explaining the nature of my invention may be made by those skilled in the art without departing from the spirit and scope of the invention as expressed in the

appended claims; and it is therefore intended that these details be interpreted as illustrative and not in a limiting sense.

Having thus described my invention and illustrated its use what I claim as new and desire to secure by Letters Patent is:

1. A fastening device comprising a binding member having a free operative end shaped to provide at least one one-way tooth, and an independently applicable complementary locking member therefor provided with means for permitting irremovable engagement thereof over said free end, said locking member comprising an apertured casing through which said free end may be threaded in either direction, and said means comprising an expansible resilient ring inaccessibly freely and totally disposed within said casing and engageable with said tooth in a manner which permits movement of the end only in the entering direction. 75 80 85

2. A fastening device comprising a stud having an enlarged base, a shank, a mid-portion adjacent to and wider than the latter to provide an abrupt shoulder between the shank and the mid-portion, and an operative free end wider than the mid-portion to provide an abrupt shoulder between the free end and the mid-portion, said stud being insertable through elements to be bound together 90 95 to position said elements on said shank and to temporarily lock them in back of said first mentioned shoulder, and an apertured locking member applicable over said free end, said locking member being provided with 100 means for inseparably engaging said member with the stud, by engagement thereof in back of said second mentioned shoulder, said means permitting movement of the locking member over said free end onto said mid-portion but not back again, whereby the elements to be bound together will be irremovably retained between said base and said member. 105

In testimony whereof I have hereunto signed my name.

HENRY E. KONDOLF.
